UNITED STATES PATENT OFFICE

TYRRELL H. DUNCOMBE, OF MIAMI, FLORIDA

AEROPLANE

Application filed June 28, 1929. Serial No. 374,312.

The present invention pertains to a novel aeroplane having particular reference to the class of aeroplanes commonly known as helicopters.

5 The primary object of the present invention is to devise an aeroplane capable of materially decreasing the hazard of flying customarily found in aeroplanes of the present day construction and in addition to provide an aeroplane which may rise vertically from a given point, which will hover over a given point, and which will descend and land upon a limited space.

Another object of the present invention is 15 to devise an aeroplane incorporating all the advantages of the usual monoplane or biplane type, having wings, fuselage and a propeller, to sustain horizontal flight, with the additional advantage of a helicopter. To 20 attain this object an aeroplane of the monoplane or biplane type is provided with a vertical shaft to extend upwardly above the wings and fuselage, being rotated with an independent motor from the ordinary motor in 25 these types of aeroplanes. A propeller is keyed to move longitudinally upon the shaft to rotate therewith in such a manner that when the shaft is idle the propeller rests at the lowermost point on the shaft and when 30 the shaft is rotated the propeller is caused to rise. The propeller when rotated with sufficient speed slides vertically upon the shaft and the outermost points of the propeller in 35 revolving and rising describe a helix in the air. An obstructing member is placed on the end of the shaft and by the time the propeller rises to the point when it comes in contact with the obstruction it is revolving with sufficient speed to lift the aeroplane from the 40 ground to take vertical flight. When a desirable height has been attained the forward propeller is employed to cause the aeroplane to assume horizontal flight.

45 With these and other objects in view my invention is hereinafter fully set forth and more particularly pointed out in the appended claims, reference being had to the accompanying drawings, in which

50 Figure 1 is a perspective view of an aero-

plane constructed in accordance with the present invention, and

Figure 2 is a transverse cross sectional view through the aeroplane.

Like characters of reference are employed 55 to designate the corresponding parts throughout.

The present invention is constructed for 60 purposes of illustration upon an ordinary monoplane having a fuselage 1, wings 2 and a propeller 3, for sustaining the aeroplane in horizontal flight. The upper part of the fuselage is formed into a suitable housing 4 to support a secondary power unit or motor 5 having a shaft 6 extending approximately 65 vertically therefrom. The shaft 6 is provided with the longitudinal spline 7 and with a lifting propeller 8 to rotate therewith yet free to move longitudinally upon the shaft.

The upper end of the shaft 6 is provided 75 with a head 9 to prevent the lifting propeller 8 from leaving the end of the shaft when the propeller is caused to rise by rotation of the shaft by the motor 5. The lifting operation is caused by rotation of the shaft 6, in turn causing the lifting propeller to rise and by the time it comes in contact with the head 9 it is revolving with sufficient speed to lift the aeroplane. The rising of the propeller 8 is rapid and to avoid a jar 80 by the propeller suddenly contacting with the head 9 there is provided a helical spring 10 surrounding the shaft 6 above the propeller to cushion the impact with the head. Similarly there is provided a helical spring 85 11 surrounding the shaft 6 below the propeller to cushion any jar which otherwise might be caused by the propeller settling to the lower portion of the shaft when the motor 5 is no longer operated.

The motor 5 is to be provided with any 90 suitable clutch mechanism and is to be operated entirely independent from the motor and propeller 3. The present construction permits the motor 5 to rotate rapidly 95 enough to revolve the propeller 8 at a sufficient speed whereby the latter displaces sufficient air to cause the aeroplane to rise vertically, this speed of the propeller being attained before the propeller reaches the 100

head of the shaft when it reacts as resistance against rotation of the motor 5. In other words before the propeller 8 strikes against the head 9 there is not a very great load upon the motor which permits the motor to attain maximum speed before the load is thrust upon it.

Although a specific embodiment of my invention has been illustrated and described 10 it is to be understood that various alterations may be made in the details of construction without departing from the spirit of the invention as depicted in the following claims.

What I claim as my invention is:

15 1. The combination with an aeroplane having a fuselage, wings and a motor driven vertically disposed propeller, of a vertically extending rotatable shaft, a propeller splined to said shaft to rotate therewith and 20 to move longitudinally thereon, a head on 85 said vertical shaft for limiting the longitudinal movement of said propeller, and resilient means between said propeller and said head for cushioning any impact of said 25 propeller with said head.

2. The combination with an aeroplane having a fuselage, wings and a motor driven vertically disposed propeller, of a motor supporting housing formed in the upper part of 30 said fuselage, a vertical shaft rotated by said 95 motor, a lifting propeller splined to said shaft to rotate therewith and to move longitudinally thereon, and resilient means limiting the longitudinal movement of said propeller.

3. The combination in an aeroplane of a 40 vertically extending motor driven splined shaft, a propeller mounted upon said shaft to slide longitudinally thereon, positive means for limiting the sliding movement of said propeller, and resilient means interposed between said positive means and 100 said propeller.

4. The combination in an aeroplane of a 45 vertically extending motor driven splined shaft, a propeller mounted upon said shaft to slide longitudinally thereon, a head on 110 said shaft for limiting longitudinal movement of said propeller, and resilient means mounted between said propeller and said head.

5. The combination in an aeroplane of a 55 vertically extending motor driven splined shaft, a propeller mounted upon said shaft to slide longitudinally thereon, a head on 115 said shaft for limiting longitudinal movement of said propeller, and coiled springs surrounding said shaft for cushioning the longitudinal movement of said propeller.

60 6. The combination in an aeroplane of a vertically extending motor driven splined shaft, a propeller mounted upon said shaft to slide longitudinally thereon, a head on 120 said shaft for limiting longitudinal movement of said propeller, and a coiled spring

surrounding said shaft in a manner resisting sudden contact between said propeller and said head.

In testimony whereof I affix my signature.

TYRRELL H. DUNCOMBE.
